HARDNESS TESTING MACHINE

Douglas E. Mick, Jonesville, Mich., assignor to
General Motors Corporation, Detroit, Mich., a
corporation of Delaware

Application October 15, 1945, Serial No. 622,393

4 Claims. (Cl. 73—79)

1

This invention relates generally to apparatus for testing the hardness of materials and more particularly to an improved machine for rapidly and accurately testing the hardness of metals of the type in which the hardness of the metal is determined by the height to which a hammer will rebound after striking the object to be tested.

One object of the invention is to provide an improved hardness testing machine which is accurate and more rapid in its operation than common hardness testing machines.

Another object of the invention is to provide an improved hardness testing machine that is more rapid in operation than common hardness testing machines and at the same time is simple in its construction and does not require frequent overhauling.

It is also an object of the invention to provide an improved hardness testing machine that can be readily adjusted to accommodate different sizes and shapes of parts to be tested.

A further object of the invention is to provide an improved hardness testing machine in which both hands of the operator are free to insert and remove work being tested.

Other objects and advantages of the invention will become more apparent from the detailed description which follows. Reference is herewith made to the accompanying drawings illustrating an apparatus constructed in accordance with one embodiment of the invention.

In the drawings:

Figure 1 is a side elevational view of the complete machine.

Figure 2 is a front elevational view of the machine illustrated in Figure 1.

Figure 3 is an enlarged view of a portion of the apparatus of Fig. 1, parts being shown in section to illustrate the construction more clearly.

Figure 4 is a top plan view of a portion of the apparatus with parts broken away and in section to illustrate the construction more clearly.

Figure 5 is a partial sectional view illustrating an arrangement of needle valves for controlling air flow to operating elements of the machine.

Figure 6 is a longitudinal sectional view through a movable portion of the apparatus adapted to be moved to clamp the work to be tested to a work support or anvil and carrying a hammer adapted when released to strike the work. In this figure the parts are shown in their up positions prior to the start of a cycle of operation.

2

Figure 7 is a sectional view substantially on line 7—7 in Figure 8, parts being shown in their up positions prior to starting a cycle of operation.

Figure 8 is a sectional view of a view substantially on line 8—8 in Figure 7.

In the drawings, 10 indicates a base member having a removable work supporting anvil 11 and an upwardly extending post or column 12. 10 A head or bracket 14 carrying operating parts of the machine is adjustably mounted on the column 12 in order to accommodate work of different sizes and shapes. When in proper position for a part of particular dimensions the bracket 14 is fixed to the column by means of a hand wheel 16 which tightens a split-ring portion 18 of the bracket to the column (see especially Figure 4). In Figures 1 and 2 the base 10 of the machine is shown as supported by a bench or table 20. Suspended from the table by springs 22 is a four-way valve indicated generally at 24. Below the table is a valve 26 adapted to be operated by foot of the operator to control the operation of the four-way valve 24. These valves control air flow which actuate movable parts of the hardness testing machine as later described in detail.

Referring especially to Figure 3 (see also Figures 1, 2 and 4) there is shown a cylinder 30 supported by a hollow column portion 15 of the head or bracket 14. Within the cylinder is a piston 32, which is movable in one direction by air pressure supplied by pipe 34 and in the opposite direction by air pressure supplied by pipe 36. A rod 38 has one end fixed to the piston for movement thereby. The rod 38 extends downwardly through the hollow column 15 into and through the smaller bore of a bushing 44. In the larger bore of the bushing 44 is a cap 40 fixed to the lower end of the rod in any suitable manner as for example, by a cap screw (not shown). A collar 46 is adjustably secured to the rod 38. Surrounding the rod between the collar and the upper end of the bushing 44 is a helical spring 48. Downward movement of the piston and rod 38 will compress the spring 48 and move the bushing downwardly within the hollow column 15. The enlarged cap 40 provides a positive return of the bushing to the position shown in Figure 3 upon upward movement of the rod 38.

Fixed to the bushing 44 for movement therewith is a hanger 50, the hollow column 15 being cut away at one side to permit the hanger to extend therethrough and be movable therein. Carried by the hanger is a tubular body 52 hav-

ing a nose cap 54 removably secured thereto by screws 56. The nose cap of the tubular body when moved downward, clamps the work or part to be tested to the anvil during the testing operation. Screws 57 secure the bushing, hanger and tubular body 52 to one another.

Fixed to the tubular body 52 and movable thereby is a small cylinder 58 having a piston 60 therein. A flexible air line 62 is connected to the cylinder 58 above the piston 60 for moving the latter in a downward direction while a flexible air line 64 is connected to the cylinder 58 below the piston for moving the same in the opposite direction. A rod 66 is connected at one end to the piston 60, and its other end is connected to a pin 68. The pin passes through a slide 70 movable within a guide groove 72 formed in the outer wall of one side of the tubular body 52. The inner end of the pin 68 is connected to a clutch sleeve 74 mounted for up and down movement within the tubular body 52. The tubular body 52 has an elongated slot 75 in which the pin 68 is moved during relative movement of the pin and clutch sleeve with respect to the tubular body 52 caused by movement of the piston 60 in cylinder 58. The upper end portion of the clutch sleeve is tapered outwardly at 76 to form a cone surface. The clutch sleeve also is slotted at 77.

Within the clutch sleeve 74 is another sleeve 78, the upper end portion of which has a plurality of similar slotted portions 80 within which are similar steel balls 82 which in the position shown in Figure 8 contact the tapered portion of the clutch sleeve. Sleeve 78 is also slotted at 84. Between the lower end of the clutch sleeve 74 and sleeve 78 is a friction spring 86. A screw 88 in threaded engagement with the clutch sleeve is movable in an opening 90 in the sleeve 78 (see Figure 6). Within the lower end of the sleeve 78 is a pilot sleeve 92 to which is fixed a latch 94. The pilot sleeve has an internal flange 96 which in the position shown in Figure 7 is in engagement with and supports an elongated hammer 98 having a point or tip 100 for engaging the part to be tested. This tip is preferably a diamond point. In the position shown in Figure 7 the steel balls 82 are pressed into contact with the hammer by the camming action of the cone surface 76.

The lower end of sleeve 78 has threaded thereto a ring 102 having an inwardly extending flange 104 acting as a stop for a pilot sleeve 92. In Figure 7 there is shown a trigger 106 pivoted at 108 to the tubular body 52 and movable in a slot 109 therein. The trigger has a dog 110 in latching engagement with the latch 94 in the position shown in Figure 7. The trigger also has finger 112 adjacent the upper end thereof. A leaf-spring 114 is shown biasing the trigger to the right in Figure 7 into latching engagement with the latch 94. A suitable trigger housing 116 is secured to the tubular body 52.

Within the tubular body 52 above the clutch-sleeve and secured to the former by a screw 118 is a guide bushing 120 through which the upper portion of the hammer passes. The upper end of the hammer is adapted to move the operating rod 122 of a dial indicator 124. This action occurs on upward movement of the pistons in cylinders 30 and 58. The indicator is removably secured to the upper end of the tubular member 52 by means of a thumb screw (see Figure 2).

In Figures 1 to 5, inclusive, are illustrated the means for controlling air flow to actuate the pis-

tons of the hardness testing machine. Fixed to the bracket 14 is a valve-body 130 which has passages 132 and 134 therein connected by flexible air lines 136 and 138, respectively, to the four-way valve 24. Passage 132 in the valve body 130 branches to form two passages 140 and 142. An adjustable needle valve 144 controls air flow through passage 140 and an adjustable needle valve 146 controls flow through passage 142. The passage 140 is connected by pipe 34 to the upper end of cylinder 30, while passage 142 is connected by flexible air line 62 to the upper end of the small cylinder 58. The respective needle valves are so adjusted that the piston 60 in its downward movement in small cylinder 58 lags behind the piston in the cylinder 30. The passage 134 in the valve-body 130 also has two branches 148 and 150 having adjustable needle valves 152 and 154, respectively, therein for controlling air flow therethrough. Branch-passage 148 is connected by the pipe 36 to the lower end of cylinder 30, while branch-passage 150 is connected by the flexible air line 64 to the lower end of small cylinder 58.

Air for operating the pistons is supplied to the inlet of the four-way valve 24 from air line 160 leading to any suitable source of air under pressure. An air line 162 branching from the line 160 leads to the foot-operated valve 26. An air line 164 leads from the foot-operated valve 26 to the four-way valve 24 for operating a piston 166 therein, which in turn operates a pivoted arm 168 of the four-way valve for operating poppet valves of the four-way valve for controlling the flow of air to the pistons 30 and 58. Two of the operating rods for the poppet valves are shown at 170 and 172. When the foot pedal 174 of the foot-operated valve 26 is depressed the piston 166 of four-way valve 24 is moved in one direction to permit air from the pressure supply line 160 to pass by way of the four-way valve 24, air line 136, passage 132 in valve-body 130, branch passages 140 and 142, pipe 34 and flexible air line 62 to the upper ends of cylinders 30 and 58 thus pushing down the pistons therein. As the pistons move down air from below the pistons in cylinders 30 and 58 passes by way of pipe 36, air line 64, branch passages, 148 and 150, passage 134, and flexible air line 138 to the four-way valve 24 where it is exhausted to the atmosphere. Releasing of the foot pedal of valve 26 causes movement of piston 166 of the four-way valve 24 to thereby actuate the valve to cause air under pressure to flow from the source of supply through flexible air line 138 to passage 134 in valve-body 130, needle valve controlled branch passages 148 and 150, pipe 36 and air line 64 to the bottoms of cylinders 30 and 58 to cause upward movement of the pistons in these cylinders. Air from above these pistons travels back through the pipe 34, air line 62, branch passages 140 and 142 controlled by needle valves, air passage 132 in valve-body 130 and flexible air line 136 to the four-way valve where it is exhausted to the atmosphere. Any four-way valve or valve capable of controlling a double acting air cylinder may be employed. In place of being operated by the pneumatic means illustrated, the four-way valve may also be operated electrically or by a cam operated, variable speed, toggle pilot valve, or by other suitable means.

The operation of the apparatus in testing the hardness of materials will now be summarized. The part to be tested is laid on the anvil 11. The foot pedal of valve 26 is depressed to actuate the

four-way valve 24 to permit air under pressure to flow into the upper end of cylinder 30, thus forcing down the piston 32 therein. By means of the rod 38 and spring 48 downward movement of the piston 32 moves downwardly the hanger 50 and tubular body 52 until the work is clamped to the anvil by the nose cap 54 carried by tubular body 52. Any overtravel of the piston 32 is taken up by spring 48. Lagging slightly behind the large piston, due to suitable adjustment of the needle valves 144 and 146, the small piston 60 in cylinder 58 also moves downward. The needle valves are so adjusted that the hammer is not released until after the work is clamped to the anvil. By means of rod 66 connected to piston 60, the pin 68 is moved downward. Pin 68 in turn moves the clutch sleeve 74 downward within the tubular body 52, the pin moving in the elongated slot 75 in the tubular body 52. During most of the downward movement of the clutch sleeve 74 the hammer 98 is held stationary by the pilot sleeve 92, which in turn is held by the dog 110 of the trigger 106 pivoted to the tubular body, the spring 114 biasing the dog into latching engagement with the latch 94 on the pilot sleeve. The sleeve 78 travels downward with the clutch sleeve 74. Just before the clutch sleeve 74 reaches the bottom of its travel, the upper end of the slot 84 in sleeve 78 contacts the upper end of latch 94. Sleeve 78 now remains stationary while clutch sleeve 74 travels approximately .020" farther down. During this short travel the steel balls 82 are held stationary by the sleeve 78 and as the outwardly tapered surface 76 of clutch-sleeve 74 travels downward the jamming contact between the steel balls and the hammer 98 is broken. The upper end of the slot 77 in clutch sleeve 74 now presses against the finger 112 at the upper end of the trigger 106 causing the trigger to move outward about its pivot 108, thereby releasing latch 94. When the latch is thus released the hammer 98 and pilot sleeve 92 drop by means of gravity and the diamond point of the hammer strikes the part to be tested causing the hammer to rebound upward a distance dependent on the hardness of the material. The greater the hardness the greater the rebound. Pilot sleeve travels downward a short distance farther than the hammer in its downward movement. The pilot sleeve moves down until it hits the flange 104 of ring 102 which is threaded on the lower end of sleeve 78. The sleeve 78 which has been held up by the friction spring 86 is forced downward by the blow to its original position relative to the clutch-sleeve 74. This allows the balls 82 to drop against the cone surface 76. Although the hammer can still travel upward on its rebound the instant it reaches the top of its travel the balls jam and prevent the hammer from dropping down. The operator now releases the foot pedal of the valve 26 and air now enters the bottom ends of cylinders 30 and 58 (through the action of the four-way valve 24) and the pistons 32 and 60 are raised to their original up position shown in Figure 3. Upward movement of piston 32 unclamps the part being tested. Upward movement of piston 60 raises clutch sleeve 74, sleeve 78 and pilot sleeve 92. As soon as the clutch sleeve raises from the upper finger of the trigger, the spring 114 biases the trigger into latching engagement with the latch 94 on the pilot sleeve 92. The hammer 98 is held by the cone clutch and it raises with the clutch sleeve 74. Contacting the rod 122, it transfers the rebound height to the dial indicator 124. This

reading is held until the next piece is tested or until the hammer is dropped without a piece in the machine. In this latter case there will be no rebound and no reading will be recorded. The needle of the dial indicator will then rest at zero.

It will be noted that both hands of the operator are free at all times to load and unload parts being tested. The machine is rapid in operation and gives most accurate readings.

10 Various changes and modifications may be made in the embodiment of my invention illustrated and described herein without departing from the principles of my invention.

I claim:

15 1. In a hardness testing machine, a base, an anvil supported thereby, a post rising from said base, a bracket adjustably mounted on the post for adapting the machine to work of different sizes, a hollow column carried by the bracket, 20 a first fluid pressure cylinder carried by the hollow column, a first piston in said cylinder, a sleeve in the hollow column below the cylinder, a piston rod having one end fixed to the piston and its other end extending into said sleeve, a 25 spring connection between the sleeve and rod forming a resilient connection between the two, a tubular member supported from the sleeve for movement therewith and adapted to be moved thereby to clamp work to be tested to the anvil, 30 a releasable hammer within the tubular member, a second fluid pressure cylinder carried by the said tubular member and movable thereby, a second piston in said second cylinder, means actuated by the second piston for releasing the 35 hammer whereby the same may fall, means for controlling flow of pressure fluid to the two cylinders so that the second piston is actuated to release the hammer after the work has been clamped to the anvil, the hammer then falling and striking the work and rebounding to a height dependent on the hardness of the work, and means for measuring the amount of rebound of the hammer.

40 2. In a hardness testing machine, a base, an anvil supported thereby, a post rising from said base, a bracket adjustably mounted on the post for adapting the machine to work of different dimensions, a hollow column carried by the bracket, 45 a first fluid pressure cylinder carried by the hollow column, a first piston in said cylinder, a sleeve in the hollow column below the cylinder, a piston rod having one end fixed to the piston and its other end extending into said sleeve, a 50 spring between the sleeve and rod forming a resilient connection between the two, a tubular member movable with the sleeve and adapted upon downward movement of the first piston to clamp work to be tested to the anvil, a releasable hammer within the tubular member, a second fluid pressure cylinder carried by the said tubular member and movable thereby, a second piston in 55 said second cylinder, means actuated by downward movement of the second piston for releasing the hammer whereby the same may fall by gravity, means including adjustable needle valves for controlling flow of pressure fluid to the two cylinders so that the second piston is actuated to release the hammer after the work has been clamped to the anvil, the hammer then falling and striking the work and rebounding to a height dependent on the hardness of the work, means for holding the hammer at its limit of rebound, 60 and means for measuring the amount of rebound of the hammer upon upward movement of the two pistons.

65 70 75

3. In a hardness testing machine, a work support, a tubular member, a releasable hammer within the tubular member, a first fluid pressure cylinder, a first piston therein, means for connecting the piston and tubular member whereby the piston may move the tubular member to clamp the work between the tubular member and the work support, a second fluid pressure cylinder carried by the tubular member and movable thereby, a second piston in said second cylinder, means actuated by the second piston for releasing the hammer whereby the same may fall, means for controlling flow of pressure fluid to the two cylinders so that the second piston is actuated to release the hammer after the work has been clamped to the support, the hammer then falling and striking the work and rebounding to a height dependent on the hardness of the work, and means for measuring the amount of rebound of the hammer.

4. In a hardness testing machine of the type in which the hardness of material is determined by the height to which a falling hammer will rebound upon striking the work to be tested, the combination which includes, a work support, a movable tubular member above the work support, a releasable hammer within said tubular member, pneumatic means for moving the tubular

member to clamp the part being tested to the work support, an air cylinder carried by the tubular member and movable thereby, a piston in said cylinder, means actuated by the piston for releasing the hammer, and means for controlling flow of air to said pneumatic means and to said air cylinder to actuate the piston to operate automatically said hammer releasing means only after said pneumatic means has moved the tubular member into work clamping position, said hammer when released falling and striking the work and then rebounding to a height dependent on the hardness of the material being tested.
